UNITED STATES PATENT OFFICE.

PAUL LESTER PARSONS, OF BELVIDERE, ILLINOIS, ASSIGNOR TO PARSONS CASKET HARDWARE COMPANY, OF BELVIDERE, ILLINOIS, A CORPORATION OF ILLINOIS.

DESIGN FOR A CASKET-HANDLE LUG PLATE.

Application filed March 29, 1926. Serial No. 17,096. Term of patent 7 years.

To all whom it may concern:

Be it known that I, PAUL LESTER PARSONS, a citizen of the United States, residing at Belvidere, in the county of Boone and State of Illinois, have invented a new, original, and ornamental Design for a Casket-Handle Lug Plate, of which the following is a specification, reference being had to the accompanying drawing, forming a part thereof.

Referring to the drawing—

Fig. 1 is a front elevation of the casket handle lug plate showing my new design; and

Fig. 2, a side elevation of the casket handle lug plate.

I claim:

The ornamental design for a casket handle lug plate as shown.

In testimony whereof I affix my signature.

PAUL LESTER PARSONS.
